UNITED STATES PATENT OFFICE.

WILLIAM D. MOUNT, OF SALTVILLE, VIRGINIA, ASSIGNOR TO THE MATHIESON
ALKALI WORKS, A CORPORATION OF VIRGINIA.

ROTARY KILN.

1,179,952.

Specification of Letters Patent.

Patented Apr. 18, 1916.

Application filed January 11, 1916. Serial No. 71,399.

To all whom it may concern:

Be it known that I, WILLIAM D. MOUNT, a citizen of the United States, residing at Saltville, in the county of Smyth and State 5 of Virginia, have invented certain new and useful Improvements in Rotary Kilns, of which the following is a full, clear, and exact description.

This invention relates to rotary kilns 10 which, as is well known, comprise a long hollow cylinder arranged at a slight incline and provided with means for imparting to the kiln a slow rotary movement; the material to be treated is fed to the kiln at its 15 upper end and comes into intimate contact with the heated gases of combustion which pass through the kiln in the opposite direction.

Kilns of this general character are in 20 common use, but difficulties have been encountered in their use where the material to be treated is of such a character that it adheres to the walls of the kiln, for the entire surface of the wall soon becomes coated 25 with a layer of the material which increases in thickness as more material is fed to the kiln until the kiln becomes choked. This condition exists in the treatment of many kinds of material, and as an example moist 30 pulverulent lime-stone may be referred to. As is well known, this material is obtained as a by-product when soda-ash is treated with lime to produce caustic soda, and is then afterward burned in a rotary kiln to 35 reconvert it into lime when it may again be used in the production of more caustic soda.

This invention, while primarily designed 40 to overcome the difficulty referred to in the treatment of this material in a rotary kiln, is not limited to it and consists of a rotary kiln having a plurality of dislodging members mounted upon the wall thereof which may be actuated to dislodge the adhering material without stopping of the kiln. 45 Where the material to be treated is such that it is only while it is in moist condition that it adheres to the surface of the lining wall, as in the example cited, then it is only necessary to provide these dislodging members adjacent the feeding zone of the kiln, although they may be extended the entire 50 length thereof if desired.

In the preferred construction, the dislodging members each comprises a plunger having 55 a head or plate inset into the kiln so that

its surface will be flush with the surface of the lining wall of the kiln and form a part thereof during normal conditions. The plungers are spring-actuated and have their ends extending exteriorly of the kiln so that 60 they may be struck as the kiln rotates to force the plunger inwardly and thus cause the material adhering to the wall to be forcibly separated therefrom.

The invention also consists of a plurality 65 of angularly disposed blades or flights mounted on the lining wall and arranged to form a helix which serves as a screw conveyor to feed the material along the kiln. These blades are interposed between the 70 dislodging members or plates in such a manner as to not interfere with the proper actuation of the latter, and in one practical construction, the portion or zone of the kiln which is provided with the dislodging plates 75 or members is composed of a plurality of axially arranged annular rings which form the lining wall, each ring consisting of a plurality of segmental portions which are bolted together. The blades are carried by 80 some of these segmental pieces and extend diagonally thereacross, the blades of the various rings being arranged in substantially helical form. The remaining segments of 85 each ring carry the dislodging members, which in adjacent rings are disposed in staggered relation so as to insure the complete removal of the substance from the walls.

The invention may also be understood 90 from an illustrated embodiment of the invention taken in connection with the description thereof, and in the accompanying drawings: Figure 1 is a central section through a kiln constructed in accordance with the principles of my invention, only a 95 sufficient part of the kiln being shown to disclose the invention; Fig. 2 is a development of a section of the feeding end of the kiln; Fig. 3 is a detail of the connection which holds the blades or flights in place; Fig. 4 100 is a transverse section on the line 4-4 of Fig. 1; and Fig. 5 is a detail of one of the annular rings which form the feeding end of the kiln.

The kiln illustrated consists of a long 105 hollow cylinder which is mounted in any desired manner in a slightly inclined position and is adapted to be rotated by any suitable mechanism, not shown. The feeding zone 1 of this kiln is shown at the left 110

of Fig. 1, and since the kiln is particularly designed for the treatment of moist pulverulent lime-stone and similar material, it is only necessary that the feeding portion of the lining wall of the kiln be provided with dislodging members to prevent it from becoming coated with the material; in the other parts of the kiln, the material is dry and will not stick to the lining walls thereof. The remaining portion of the kiln which has been designated 2 has an intermediate section thereof omitted as at 3, so as not to unduly increase the length of the drawing, and is of the usual construction consisting of an outer iron casing 4, and a lining wall 5 of fire brick or other vitreous material. The feeding zone 1 of the kiln, in the form illustrated is composed of a plurality of annular rings 6 which form the lining wall and are of the same internal diameter as the lower part of the kiln being arranged in axial alinement therewith. The rings 6 are secured together by bolts or other fastening devices passing through flanges 7' projecting exteriorly from the peripheral edges of the rings. As will be clear from Fig. 4, each annular ring is preferably made in sections, six such segmental sections being shown and designated 7 to 12, respectively, the segmental sections being united by bolts passing through lugs 13 carried by each of the sections. Surrounding the rings 6 is an outer casing 14 which forms a continuation of the outer casing or shell 4 of the lower part of the kiln. This casing is secured to the end ring by means of an annular flange or header 15'.

Each of the rings 6 has mounted thereon a plurality of dislodging devices or members and in the form illustrated each of these devices is of the same construction and consists of a plunger 15 which has a broad base forming a rectangular plate 16. This plate is inset in a correspondingly shaped opening in the ring, while surrounding the plunger is a cylinder or sleeve 17 having a curved flange or base 18, which is secured to the exterior surface of the ring and against which the base or plate 16 is adapted to rest in the normal operation of the kiln, the flange 18 being so spaced from the inner surface of the ring 6 that the surface of the plate 16 will be flush with the inner surface of the ring forming the lining wall of the kiln. In other words, during the normal conditions the plates 16 form a part of the lining wall of the kiln. The sleeve or cylinder 17 surrounding the plunger 15 is of a height to fit between the inner ring 6 and the outer casing 14 and hence will also serve as a spacing member to maintain the outer casing in position. Mounted on the plunger 15 in axial alinement is a plunger rod 19 which passes through an opening in the casing 14 and is provided

with an enlarged head or knob 20. Surrounding the plunger rod is a tension spring 21, one end of which bears against the knob 20 and the other against the casing 14 so that the plunger 15 and its base or plate 16 is normally maintained in a position in which the face plate and lining wall are flush.

In the construction shown, two such dislodging devices or members are mounted upon four of the segments of each annular ring while two oppositely disposed segments carry angularly-disposed blades which form a screw conveyer. The segments which carry the blades are each provided with four openings 22, arranged diagonally across the flange and the blades which have been designated 23 are provided with lugs 24 which are adapted to pass through these openings. The lugs 24 are provided with square recesses into which two wedge-shaped blocks 26 fit, while passing through the blocks is a bolt and nut 27 which, when tightened, moves the blocks together and hence draws the blades into firm engagement with the walls of the ring and the blades are rigidly held in position.

Referring now to Fig. 2, a development of a portion of the kiln is illustrated which shows the preferred arrangement of the dislodging members and blades, the plates 16 of the dislodging members being arranged in staggered relation so as to insure the complete removal of the layer of material which forms on the lining wall, while the blades are arranged in substantially helical form thus providing a screw conveyer for feeding the mass of material entering through the front end of the kiln to the lower part thereof.

The operation of the kiln is obvious. Let us assume that the heated gases or products of combustion pass through the kiln from right to left as shown in Fig. 2, and the material, such as moist pulverulent lime-stone, is fed into the front end of the kiln. As the kiln revolves, the screw flight or conveyer formed by the blades will positively advance the material toward the lower end of the kiln, while at the same time the lime-stone is being acted upon by the heated gases passing through in the opposite direction to convert the lime-stone into lime. After the kiln has been in operation for sometime, a coating of the material will form upon the lining wall composed of the rings 6. When such a layer forms, a workman strikes each knob or head 20 a heavy blow with a sledge or other implement as they pass by him in the rotation of the kiln. This blow forces each plunger radially inwardly and will forcibly separate the material from the wall of the kiln after which the plunger returns to its normal position in which it is flush with

and forms a part of the lining wall of the kiln. The kiln can therefore be operated continuously and the lining walls of the same kept comparatively clean.

5 In so far as I am aware, it is broadly new with me to provide movable members on the lining wall of a kiln which may be actuated to forcibly separate the material from the lining wall and it is my intention to cover this feature broadly as will be evidenced by the scope of the claims appended hereto.

I claim:

1. A rotary kiln having a plurality of 15 movable wall sections forming a part of its lining wall and constituting dislodging members.

2. A rotary kiln having a plurality of inwardly movable dislodging members 20 mounted on the lining wall thereof.

3. A rotary kiln having a plurality of movable dislodging members mounted on the lining wall thereof, and means for moving said members inwardly.

25 4. A rotary kiln having a plurality of movable dislodging members mounted on the lining wall thereof, said members each having a part extending exteriorly of the kiln and adapted to be struck to force the 30 dislodging member inwardly.

5. A rotary kiln having a plurality of dislodging members mounted on the lining wall thereof, each of said members comprising a spring actuated plunger having a 35 part extending exteriorly of the kiln.

6. A rotary kiln having a plurality of dislodging members mounted on the lining wall thereof, each of said members comprising a plunger having a base, the surface 40 of which is flush with the surface of the lining wall of the kiln.

7. A rotary kiln having a plurality of dislodging members mounted on the lining wall thereof, each of said members comprising a plunger having an enlarged base 45 having its surface flush with the lining wall of the kiln, each of said plungers having a part extending exteriorly of the kiln and adapted to be struck to force the plunger 50 inwardly.

8. A rotary kiln having a plurality of dislodging members mounted on the lining wall thereof, in spaced relation and forming circular rows, the dislodging members 55 in adjacent rows being disposed in staggered relation.

9. A rotary kiln comprising a plurality of axially aligned annular rings, the inner surfaces of which form a portion at least

of the lining wall of the kiln, a plurality of 60 dislodging members mounted on each of said rings in spaced relation therearound.

10. A rotary kiln comprising a plurality of axially aligned rings, the inner surfaces of which form a portion at least of the lining 65 wall of the kiln, a plurality of dislodging members mounted on the inner surfaces of said rings, said dislodging members having their faces flush with the surfaces of said rings. 70

11. A rotary kiln comprising a plurality of axially aligned rings, the inner surfaces of which form a portion at least of the lining wall of the kiln, a plurality of dislodging members mounted on the inner surface 75 of each of said rings, each of said dislodging members comprising a plunger having an enlarged base fitting into the recess of the ring, said plunger having a part connected thereto extending exteriorly of the 80 kiln and adapted to be struck to force the plunger inwardly.

12. A rotary kiln comprising a plurality of axially aligned rings, the inner surfaces of which form a portion at least of the lining 85 wall of the kiln, each of said rings comprising a plurality of separable segments secured together, dislodging members carried by some of said segments and inwardly projecting blades carried by the 90 other of said segments, said dislodging members of adjacent rings being disposed in staggered relation and said blades on said rings being disposed to substantially 95 form a helix.

13. In a rotary kiln, a plurality of axially aligned rings, the inner surfaces of which form a portion at least of the lining wall of the kiln, inwardly projecting segmental-shaped blades carried by each of said rings, 100 dislodging members mounted on the inner surface of each of said rings, and said blades on the rings being disposed in substantially helical form.

14. In a rotary kiln, a plurality of segmental-shaped blades projecting inwardly from the lining wall thereof, said blades being disposed around the lining wall in substantially helical form and a plurality of 105 dislodging members mounted on said lining 110 wall and disposed in staggered relationship.

In witness whereof, I subscribe my signature in the presence of two witnesses.

WILLIAM D. MOUNT.
